(57) **CLAIM**

The ornamental design for scissors, as shown and described.

DESCRIPTION

FIG. 1 is a perspective view of first embodiment of scissors showing my new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof;

FIG. 8 is a bottom plan view thereof;

FIG. 9 is a view of use state thereof;

FIG. 10 is a perspective view of second embodiment of scissors showing my new design;

FIG. 11 is another perspective view thereof;

FIG. 12 is a front view thereof;

FIG. 13 is a back view thereof;

FIG. 14 is a left side view thereof;

FIG. 15 is a right side view thereof;

FIG. 16 is a top plan view thereof; and

FIG. 17 is a bottom plan view thereof; and,

FIG. 18 is a view of use state thereof.

The broken lines in the drawings depict portions of the scissors that form no part of the claimed design.

1 Claim, 18 Drawing Sheets
